(57) **CLAIM**

The ornamental design for a jewelry storage box, as shown and described.

DESCRIPTION

FIG. 1 is a front and top perspective view of a jewelry storage box, showing my new design;
FIG. 2 is a rear and bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is another perspective view thereof, shown in an alternative position.

The broken lines on the front face of the drawer and the top lid depict stitching that forms a part of the claimed design. The remaining broken lines in the figures illustrate portions of the jewelry storage box that form no part of the claimed design.
